UNITED STATES PATENT OFFICE.

HENRY BORGmann, OF WASHINGTON, DISTRICT OF COLUMBIA.

FOOT REST.

Application filed July 29, 1926. Serial No. 125,799.

The device forming the subject matter of this application is a foot rest, adapted to be mounted on a boot-blacker's stand, and so constructed that, when not in use, it may be 5 swung into an out-of-the-way position, beneath a part of the stand. One object of the invention is to improve generally and to enhance the utility of devices of that sort to which the invention appertains; but, more 10 particularly, it is the invention of a novel brake, which characterizes the present case, the brake serving to prevent the foot rest from swinging downwardly, with unnecessary force, and with objectionable noise, 15 when the latch mechanism, which holds the foot rest in operative position, is released.

A preferred form has been shown, but it will be understood that a mechanic, working within the scope of what is claimed, may 20 make such changes as his skill may suggest, without departing from the spirit of the invention.

In the drawings:—

Figure 1 is a front elevation;
25 Figure 2 is a section on the line 2—2;
Figure 3 is a plan of the foot rest;
Figure 4 is a plan of the complete article;
Figure 5 is a section on the line 5—5.

The device is made of metal and includes 30 a base plate 1 having holes 2 adapted to receive securing elements, whereby it may be held on the under surface of a part 4 of a shoe-blacker's stand.

The base plate 1 is provided intermediate 35 its ends and near to its forward edge with depending ears 4 connected by a pivot element 5 on which a latch 6 is mounted to swing, the latch having a recess 7 in its rear edge, and being supplied with a finger 8 which extends up into the recess. The latch 40 has a beveled edge 9, located below the finger 8. A spring tongue 10 is held by a securing element 11 on the forward edge of the latch 6 and bears against the edge of the base 45 plate 1, to resist yieldingly, the forward swinging movement of the latch 6, and to hold the latch about in the vertical depending position of Figure 5. Near to its ends, the base plate 1 is supplied with downwardly 50 extended bearings 12.

A shaft 14 is mounted to rock in the bearings 12 and upwardly curved arms 15 are secured at 16 to the ends of the shaft 14, outwardly of the bearings 12. Each arm 15 at 55 its upper end terminates in a rearwardly extended lug 17 and in a forwardly extended

lug 18, the lug 18 being joined integrally to a T-shaped head 19 including a shank 20 and a cross piece 21. A foot rest 22 is provided and is off-set to form a shoulder 23 against 60 which the heel of the shoe to be blacked, abuts. This shoulder at 23 engages behind the cross piece 21. The forward part of the foot rest 22 rests on the shank 20 of the head 19, and the rear part of the foot rest 65 22 engages directly with the lug 17. Securing elements 24, such as bolts, connect the foot rest 22 with the cross piece 21 of the head 19. The general construction is such that the foot rest 22 is attached to the arm 70 16 in a very secure way.

The shaft 14 has a curved keeper 25 provided with a seat 26. When the foot rests 22 are to be used, they are swung upwardly and forwardly, from the dotted line position shown at 27 in Figure 5, to the solid line position of that figure, the keeper 25 tilting the latch 6, and the finger 8 of the latch engaging in the seat 26 to hold the foot rest 22 elevated. When it is desired to 80 dispose the foot rests 22 in an out-of-the-way position, so that the garments of the patron will not be torn as he climbs down from the stand, the latch 6 is disengaged from the keeper 25, and the arms 15, together with 85 the foot rests 22, swing downwardly into the position indicated at 27 in Figure 5, the shaft 14 rocking in the bearings 12. The foot rests 22, the arms 15, and the keeper 25, being made of iron, have considerable mass, 90 and the result is that when the foot rests 22 swing downward to an inoperative position, they do so with considerable force, often with a crash or bang which is disquieting to the patron, and productive of other annoyances. In order to obviate a too rapid 95 downward swinging of the foot rests 22 there is provided a brake mechanism which will now be described.

The base plate 1 carries a depending pair 100 of studs 28 located on opposite sides of the shaft 14. These studs 28 may be headed bolts, mounted detachably in openings in the base plate 1, and held against downward movement by the engagement between their heads and the base plate. A brake shoe 29, preferably in the form of a metal block, is 105 slideable on the studs 28, longitudinally thereof, and has in its upper surface a concaved seat 30 for the reception of the shaft 14. The brake shoe 29 is pushed upwardly 110 against the shaft 14 by compression springs

31, mounted on the studs 28. The springs 31 are adjusted through the instrumentality of a yoke bar 32, slideable on the studs 28 and held in adjusted positions by thumb nuts 33 threaded on the lower ends of the studs 28. The part 32 is called a yoke bar because it connects the studs 28 at points near to their lower ends, and prevents the studs 28 from being bent so that the brake shoe 29 will not slide readily on the studs. By setting the thumb nuts 33 properly, the operator can regulate the pressure of the shoe 28 on the shaft 14, and thus cause the arms 15 and the foot rests 22 to swing downwardly slowly and quietly. If for any reason, the brake shoe 29 has not been set properly with respect to the shaft 14, and if the arm 15 swings downwardly suddenly, the shock is taken up by a resilient buffer 34, generally made of rubber, and including a reduced stem 35 secured in an opening 36 in the base 1. In order to prevent the toe of the sole of the shoe from slipping sidewise on the foot rest 22, the foot rest is provided at one end with a 25 raised portion 37 having longitudinal ribs 38. What is claimed is:—

In a stand of the class described, a support, a foot rest, rotatable means on the support for mounting the foot rest for movement between a raised operative position and a lowered inoperative position, releasable interengageable latch elements respectively carried on the rotatable means and on the support, and cooperating to hold the foot rest in raised operative position, a friction brake engaging the rotatable means to retard the downward movement of the foot rest from raised operative position to lowered inoperative position when said latch elements 40 are disengaged, and mechanism for adjusting the brake to regulate the aforesaid retarding action of the brake.

In testimony that I claim the foregoing as my own, I have hereto affixed my signature.

HENRY BORGmann.
